UNITED STATES PATENT OFFICE.

JULIEN STRANDERS, OF NEW YORK, N. Y., ASSIGNOR TO AMERICAN LITHOGRAPHIC COMPANY, OF NEW YORK, N. Y., A CORPORATION OF NEW YORK.

COLLAPSIBLE DISPLAY DEVICE.

1,028,147.

Specification of Letters Patent. Patented June 4, 1912.

Application filed February 4, 1911. Serial No. 606,512.

To all whom it may concern:

Be it known that I, JULIEN STRANDERS, a subject of the King of Great Britain and Ireland, and a resident of New York, in the 5 county of Kings and State of New York, have invented certain new and useful Improvements in Collapsible Display Devices, of which the following is a specification.

This invention relates to collapsible 10 play devices and has for its object to provide a device of the character specified of simple construction and which may be readily and easily changed from a collapsed condition to a display condition and as easily 15 changed back again to a collapsed condition.

In its preferred form my improved device comprises features illustrated in the accompanying drawing wherein—

Figure 1 represents a front perspective 20 view of my device in its display condition. Fig. 2 is a plan view corresponding with Fig. 1. Fig. 3 is a rear view illustrating one embodiment of the means used for holding the device in its display condition. Fig. 25 4 is a diagrammatic plan view showing the device in its collapsed condition. Fig. 5 illustrates a modification of the means of Fig. 3.

My improved device relates directly to 30 that class of display devices which are made from sheet material such as card board and which bear on their face or faces representations of one or more articles, and are adapted to represent those articles in a realistic manner for dressing shop windows or 35 the like.

As representative of the large and widely varied class of articles suitable for display by means of my improvements I have chosen 40 bottles of an ordinary and well known form. Also I have chosen to represent a plurality of rows of such bottles arranged in pyramidal form to simulate the effect of a pyramid of real bottles.

45 Referring now more directly to the drawing, my improved device comprises a back preferably having right and left wings 2, 3 formed of one piece of material having a vertical folding crease 4, or said back may 50 comprise two separate wings 2, 3 joined by a foldable connection at 4. As illustrated said wings 2, 3 are notched or stepped at their outer edges opposite jointure 4, as at 6, 8, 10 of wing 2, and 7, 9, 11 of wing 3. 55 To opposite vertical risers as 12, 13 are

jointed or articulated opposite ends of front member 5 representing in the present instance a row of bottles. Said front member 5 is of a width preferably substantially equal to the combined width of wings 2, 3 60 from edge 12 to edge 13 so that when the device is in its collapsed condition, Fig. 4, front member 5 will lie flat against wings 2, 3 for economy of space in packing and shipping. Said front member may be 65 formed integral with back 2, 3 but I have found it more economical of material and simpler in construction to supply ears 14, 16 to front member 5 and which ears are folded back into joints and secured to the inside 70 faces of free edges 12, 13 respectively. Front member 15 representing a row of bottles similar to that of front member 5 but comprising a smaller number of bottles, has a width preferably substantially equal 75 to the combined width of said wings 2, 3 from edge 18 to edge 19 thereof. Said front member 15 is also provided with ears 20, 21 attached to the inside faces of free edges 18, 19 respectively, all similar and 80 similarly arranged to corresponding parts already described in connection with front member 5. The construction and mounting of front member 25, above front member 15 will be understood without further 85 description.

When the device is in display condition back wings 2, 3 form an angle with each other and front members 5, 15, 25 are bent into curved form all as clearly illustrated 90 in Figs. 1 and 2. If my improved device is made of card board, celluloid or any of the variety of other suitable bendable material, said front members will automatically assume the bent or curved form illustrated, when wings 2, 3 are folded up from their collapsed condition in one plane, Fig. 4 to their angular relation of Fig. 2. For maintaining my improved device in its display condition I may employ any of several devices effective to retain wings 2, 3 in their angular relation of Fig. 2. I preferably employ a tension member, as a piece of string 22, passed through hole 17 in one wing, as 2, and having a knot 23 near the 100 end of said string to prevent its pulling through said hole 17. The other end of said string I pass through hole 24 in the other wing 3 and provide a knot 27 in said string at a distance from knot 23 equal to 105 110

approximately the distance between holes 17 and 24 when wings 2, 3 are in the relative position of Fig. 2. Hole 24 is of sufficient size to allow knot 26 to pass freely there-through and, to enable string 22 to maintain wings 2, 3 in their relative angular position of Fig. 2, I provide a narrow slot 26 extending from hole 24 a short distance in wing 3, toward joint 4. Said slot 26 is sufficiently narrow to prevent the passage of knot 27 therethrough. Beyond knot 27 a free portion of string 22 is provided by which knot 27 may be engaged or disengaged with slot 26. Said free end of string 22 may terminate in a knot or button 28 large enough to prevent said free end from being pulled through hole 24.

In Fig. 5 I have illustrated the use of a cardboard or other strip 30 in place of string 22. Therein said strip 30 may be secured by any suitable means at 31 to wing 2 and provided near its other end with a step or steps 32 in lieu of knot 27 of string 22 and the hole 33 in wing 3 may be modified in shape and size as shown to allow the passage of stepped portion 34 in its wider portion and to engage steps 32 in its narrower portion. Head 35 of strip 30 may be of sufficient additional width to prevent its passage through hole 33.

As an arbitrary choice I have illustrated my device as comprising representations of several pyramided rows of bottles. It is obvious that articles other than bottles, such as packages, boxes, cans or a variety of other articles could be equally well represented. Also it is not essential to my invention that there be a plurality of rows of articles or if there is a plurality of rows that those rows be pyramided.

In view of the present advanced state of

the art in display devices various modifications of my device lying within the scope of my claims will readily occur to those skilled in the art.

45

I claim:

1. A collapsible display device including in combination, a flexible front member, two rigid back members, each having opposite parallel edges, the respective adjacent edges of each of said members being hinged together, the combined width of said back members being substantially equal to the width of said front member, and the opposite outer edges respectively of said back members being hinged to the opposite edges respectively of said front member; a cord secured to one of said back members, a hole through the other back member, said cord passing through said hole and means for securing said cord to that back member; said cord being efficient when thus secured for holding said back members in angular relation to each other and for holding said flexible front member in curved position.

60

2. A display device including in combination two rigid back members hinged together, said members having their opposite outer edges respectively stepped, a plurality of flexible front members each having their opposite edges hinged to a pair of opposite step risers of said back members and a tension member connecting said rigid back members for maintaining them in angular relation and for maintaining said front members in curved position.

65

Signed this 31st day of January 1911 before two subscribing witnesses.

JULIEN STRANDERS.
